A. Stennel.

Harness Machine,

N° 21,989.

Patented Nov. 2, 1858.

UNITED STATES PATENT OFFICE.

ADOLPH STEMPPEL, OF OQUAWKA, ILLINOIS.

MACHINE FOR CREEASING AND BLEACHING LEATHER FOR HARNESS.

Specification forming part of Letters Patent No. 21,989, dated November 2, 1858; Reissued May 31, 1859, No. 781.

To all whom it may concern:

Be it known that I, ADOLPH STEMPPEL, of Oquawka, in the county of Henderson and State of Illinois, have invented a new and 5 Improved Machine for Creasing Leather Straps and Blacking the Edges Thereof; and I do hereby declare that the following is a full, clear, and exact description of the same, reference being had to the annexed 10 drawings, making a part of this specification, in which—

Figure 1, is a vertical central section of my invention. Fig. 2, is a transverse section of ditto, taken in the line x, x , Fig. 1. 15 Fig. 3, is a horizontal section of ditto, taken in the line y, y , Fig. 1. Fig. 4, is a transverse section of ditto, taken in the line z, z , Fig. 3.

Similar letters of reference indicate 20 corresponding parts in the several figures.

This invention consists in the employment or use of creasing and embossing rollers and a pressure roller combined and arranged with two color fountains provided 25 with felt distributors the whole being arranged substantially as hereinafter shown for creasing, embossing and coloring the edges of leather straps.

To enable those skilled in the art to fully 30 understand and construct my invention I will proceed to describe it.

A, represents a suitable framing on the upper part of which two heads B, B', are placed, between which a frame C, is placed, 35 the frame working on pivots a, a , projecting from the inner sides of the heads B, B'. To the outer end of the frame C, a treadle D, is connected by a strap E, and in the inner end of the frame C, at the opposite 40 side of the pivots a, a , a roller F, is fitted, said roller being allowed to turn freely in its frame. The roller F, is toothed at one end, as shown at b , and said teeth gear into a wheel c , which is placed on one end of a 45 roller G, said roller having one of its journals fitted in the head B', and the other journal fitted in a pendent H, attached to the end of a horizontal bar I, which is secured to the upper end of the head B', see 50 Fig. 2.

In the frame C, there are placed two gages d, d' , which are secured therein by set screws e, e . These gages have their inner ends curved and they project over the roller F. 55 Each gage having a bar or plate f , attached

the object of which will be presently explained. The outer parts of the gages d, d' , are fitted in a slot or opening g , in the frame. J, is a spring which is attached to the framing A, and bears against the under 60 side of the frame C, as shown in Fig. 1.

On the roller G, there are placed two collars h, h' , and on both ends of each collar a roller i , is formed or attached, said rollers having their outer edges or parts milled 65 or formed as shown at j , so as to produce ornamental embossed lines on the strap, see Fig. 2. The inner edges or parts of the rollers are grooved as shown at k , so as to crease the strap, as will be hereinafter more 70 particularly referred to. To the head B', a plate l , is attached, said plate being slightly inclined and serving as a guide or support to the strap, properly conducting or guiding the same to the rollers which operate 75 upon it.

On the front part of the framing A, there are placed two boxes K, L, in which the usual or any proper coloring substance m , is placed. In each box there is placed a roll 80 of felt M, said rolls projecting up above the inner sides of the boxes. The felt rolls M, are saturated with the coloring substance m , and their upper edges or surfaces are kept charged therewith by capillary attraction. 85 To the box K, a bar N, is attached by a hinge or joint n . This bar serves as a weight and keeps the strap in proper position as it passes through the machine. O, is a bar 90 which serves as a support or bearing for the strap.

The operation is as follows: The strap shown in red and designated by D', is placed over the bar O, and under the weight or bar N, and passes between the saturated felt 95 rolls M, M, and then between the guides d, d' , and between roller F, and the inner rollers i, i , of the collars h, h' , the collars h, h' , being keyed on the shaft G, and the guides d, d' , being adjusted in line with the 100 collars h, h' , and the boxes K, L, are also adjusted in line with the collars. The box K, guide d , and collar h , may be adjusted; the other box, guide and collar need not be shifted. This adjustment of the above 105 named parts is necessary to admit of straps of varying widths being operated upon. The edges of the straps are colored by the felt rolls M, and the edges of the strap are creased by the grooved edges k , of the rollers 110

i, and the central portion is embossed or ornamented by the portions *j*, *j*, of the rollers *i*. The strap D, is subjected to the requisite degree of pressure by depressing the treadle 5 D, with the foot, the guides *d*, *d*', preventing the strap spreading laterally. The guides *d*, *d*', therefore perform an important function, for if the straps are allowed to expand laterally under the pressure of the 10 rollers the efficacy of the machine would be destroyed at once. The strap is made to enter between the rollers by turning the crank attached to the shaft G.

I would remark that the pressure roller 15 as well as the creasing and embossing rollers and shaft G, are of metal. In fact all the working parts are of metal.

From the above description it will be seen that straps may be creased and embossed in an expeditious and perfect manner, and various forms of rollers *i*, may be used according to the nature of the work to be performed, so that straps may be creased without being embossed.

In the drawings rollers *i*, are made on each 25 end of each collar so that the collars may be reversed on the shaft G, for effecting a change of work.

I would further remark that any irregular piece of leather may be creased equally 30 as well as a strap with parallel edges.

I do not claim broadly the employment or use of creasing and embossing rollers in connection with a pressure roller for ornamenting and creasing leather, for such device has been previously used, but 35

Having thus described my invention, what I claim as new and desire to secure by Letters Patent, is—

The pressure roller F, and the creasing and embossing rollers *i*, in combination with the color fountain K, L, and felt rolls M, M, the whole being arranged to operate as and for the purpose set forth.

ADOLPH STEMPEL.

Witnesses:

FRANCIS KOEHLER,
COZ. O. FENDAHL.
